REFRIGERATION APPARATUS

Elliott E. Grover, Springfield, and Albert E. True-love, Westfield, Mass., assignors to Westinghouse Electric & Manufacturing Company, East Pittsburgh, Pa., a corporation of Pennsylvania

Application December 30, 1939, Serial No. 311,880

13 Claims.

(Cl. 62—1)

This invention relates to refrigeration apparatus and particularly to a noise damping mounting for the refrigerant compressor and driving motor of refrigeration apparatus.

It is an object of the invention to provide an improved mounting for a motor and compressor which will effectively dampen the noise resulting from operation of the motor and compressor.

It is another object of the invention to provide an improved mounting for a motor and compressor which are supported on a plate type condenser of a refrigerating mechanism.

It is another object of the invention to provide a resilient mounting for a motor and compressor used in refrigeration apparatus, which mounting is assembled in the factory and permits both shipping and installation of the complete refrigeration apparatus without adjustment of the mounting.

These and other objects are effected by the invention as will be apparent from the following description and claims taken in connection with the accompanying drawing forming a part of this application, in which:

Fig. 1 is an elevational view of a refrigerating apparatus embodying a plate type condenser and illustrating one form of our improved noise damping mounting, parts of the refrigerating apparatus being broken away for the sake of clearness;

Fig. 2 is a partial sectional view of the hermetically sealed motor compressor unit shown in Fig. 1;

Fig. 3 is a sectional view taken on the line III—III of Fig. 1 with parts broken away for the sake of clearness;

Fig. 4 is a side view of the motor compressor unit and the bottom of the plate condenser shown in Fig. 1; and,

Fig. 5 is an enlarged view partially in section of the snubber disposed at the top of the motor compressor unit.

Referring specifically to the drawing for a detailed description of the invention, numeral 11 designates, generally, a complete refrigerating mechanism comprising a plate type condenser 12, an evaporator 13 and a hermetically-sealed motor compressor unit 14. As shown in Fig. 2, the motor compressor unit 14 comprises, for example, a reciprocating compressor 15 driven by a motor 16 through a drive shaft 17, the motor and compressor being disposed in side-by-side relation and the drive shaft 17 being substantially horizontal. A frame member 18 is disposed within a hermetically sealed casing 19 and rigidly sup-

ports the motor, compressor and drive shaft in operative relation.

As shown in Figs. 1 and 2, the compressor 15 compresses refrigerant gas and discharges the compressed gas through a conduit 21 which extends to the top of the plate condenser 12. The plate condenser 12 preferably comprises a single sheet of steel 22 provided with flanges 23 at its vertical marginal edges and having a coil of pipe 24 welded or brazed to the sheet. The sheet 22 is preferably bent to the shape shown in Fig. 3. High pressure gas from the conduit 21 discharges into the coil 24 and as it passes downwardly through the coils of the condenser the gas is liquefied by the cooling effect of the ambient atmosphere in which the condenser is disposed. A screen assembly 25 is provided at the bottom of the coil 24 and communicates with a capillary tube 26 extending from the screen assembly 25 to a refrigerated shelf 27 of the evaporator 13. The capillary tube 26 restricts and controls the flow of refrigerant liquid from the coil 24 to the evaporator 13. Refrigerant is vaporized in the evaporator and cold refrigerant vapor is returned to the interior of the hemetically-sealed casing 19 through the conduit 28, preferably in heat exchange relation with the refrigerant in the capillary tube 26. The vaporized refrigerant is again compressed by the compressor 15 and the refrigerating cycle is repeated.

As best shown in Figs. 3 and 4, brackets 29 are bolted to the flanges 23 of the condenser plate 22 near the bottom thereof. A saddle 31 is bolted to the brackets 29 and extends over the top of the motor compressor unit 14.

In order to support the motor compressor unit 14 and to dampen noises incident to its operation, two resilient mountings 32, preferably formed of rubber, are disposed between the brackets 29 and brackets 33, the latter brackets preferably being welded to the sides of the hermetically-sealed casing 19, as best shown in Fig. 3. The rubber mountings 32 are of the type shown in Fig. 5 and comprise a heavy central rubber body 34 having plates 35 vulcanized at opposite faces thereof, which plates are provided with threaded studs 36. Such a rubber mounting affords limited relative movement between the motor compressor unit 14 and the brackets 29 and effectively dampens the noise due to vibrations resulting from the unbalanced masses of the compressor 15 and motor 16.

We have found, however, that for such a mounting to be most effective, the resilient connections 32 should be so disposed that a line

passing between them passes substantially through the center of gravity of the motor compressor unit 14 and substantially perpendicularly to the drive shaft 17. By so disposing the resilient connections 32, the noises due to vibrations caused by the unbalanced masses contained in the motor compressor unit 14 transmit torsional movement to the resilient connections 32 and are effectively damped.

In order to limit the torsional movement thus transmitted, a snubber generally indicated at 37 is disposed at the top of the motor compressor unit. A bracket 38 is welded to the top of the motor compressor unit and supports a cup 39, the center of which is at a point directly above the center of gravity of the motor compressor unit 19 and in the same plane as the resilient connections 32. In other words, a plane passed between the resilient connections 32 and the center of the cup 39 would pass through the center of gravity of the motor compressor unit and would be substantially perpendicular to the drive shaft 17.

A resilient connection, generally indicated at 41, extends between the cup 39 and the saddle 31, the studs 36 of the resilient connection 41 being threaded into the bracket 38 and the saddle 31. A nut 42 retains the top stud 36 in position with respect to the saddle 31. The cup 39 is shaped so that it extends close to the side walls of the resilient connection 41 without touching them, so that limited relative movement between the motor compressor unit 19 and the saddle 31 is permitted. However, the resilient connection 41 supports little or none of the weight of the motor compressor unit 14, although after the apparatus is in operation for a considerable period of time, the resilient connections 32 may stretch slightly and place the resilient connection 41 under a small amount of tension.

From the foregoing, it will be apparent that we have provided an improved noise-damping mounting for the motor compressor unit of refrigeration apparatus and especially of refrigeration apparatus wherein the motor compressor unit is mounted on a plate type condenser.

While we have shown our invention in but one form, it will be obvious to those skilled in the art that it is not so limited, but is susceptible of various changes and modifications without departing from the spirit thereof, and we desire, therefore, that only such limitations shall be placed thereupon as are specifically set forth in the appended claims.

What we claim is:

1. In a motor compressor unit mounting, the combination of a compressor, a motor for driving the compressor, a drive shaft extending between the motor and the compressor, a structure for retaining the motor and compressor as an operative unit, a rigid structure for supporting the motor compressor unit and a noise damping mounting for the motor compressor unit comprising two resilient connections extending between said unit and said rigid supporting structure, which connections support the major portion of the weight of the motor compressor unit and are so disposed that a straight line between them passes through the center of gravity of the motor compressor unit and is perpendicular to the centerline of the drive shaft.

2. The combination set forth in claim 1 where-
in the resilient connections comprise blocks of soft rubber.

3. In a motor compressor unit mounting, the combination of a compressor, a motor for driving the compressor, a drive shaft extending between the motor and the compressor, a structure for retaining the motor and compressor as an operative unit, a rigid structure for supporting the motor compressor unit and a noise damping mounting for the motor compressor unit comprising two resilient connections extending between

10 said unit and said rigid supporting structure, which connections support the major portion of the weight of the motor compressor unit and are so disposed that a straight line between them passes through the center of gravity of the 15 motor compressor unit and is perpendicular to the centerline of the drive shaft, and said resilient connections being positioned an appreciable distance from said compressor and on opposite sides of the drive shaft, so that vibrations 20 produced by the unbalanced mass of the compressor apply rotational torque to the connections.

4. In a motor compressor unit mounting, the combination of a compressor, a motor for driving the compressor, a drive shaft extending between the motor and the compressor, a structure for retaining the motor and compressor as an operative unit, a rigid structure for supporting the motor compressor unit, a noise damping mounting for the motor compressor unit comprising two resilient connections extending between said unit and said rigid supporting structure, which connections support the major portion of the weight of the motor compressor unit and are so disposed that a line between them passes through the center of gravity of the motor compressor unit and is perpendicular to the centerline of the drive shaft, said resilient connections being positioned an appreciable distance from said compressor and opposite the side of the drive shaft, so that vibrations produced by the unbalanced mass of the compressor apply rotational torque to the connections, and means for limiting rotational movement about said resilient connec- 45 tions.

5. In a motor compressor unit mounting, the combination of a compressor, a motor for driving the compressor, a drive shaft extending between the motor and the compressor, a structure for retaining the motor and compressor as an operative unit, a rigid structure for supporting the motor compressor unit and a noise damping mounting for the motor compressor unit comprising two resilient connections extending between said unit and said rigid supporting structure, which connections support the major portion of the weight of the motor compressor unit and are so disposed that a line between them passes through the center of gravity of the motor compressor unit and is perpendicular to the centerline of the drive shaft, said noise damping mounting including a third resilient connection between the motor compressor unit and the rigid supporting structure, which connection supports little or none of the weight of the motor compressor unit but limits the magnitude of oscillatory movement about said first two resilient connections.

6. In a motor compressor unit mounting, the combination of a compressor, a motor for driving the compressor, a drive shaft extending between the motor and the compressor, a structure for retaining the motor and compressor as an operative unit, a rigid structure for supporting the motor compressor unit and a noise damping

mounting for the motor compressor unit comprising two resilient connections extending between said unit and said rigid supporting structure, which connections support the major portion of the weight of the motor compressor unit and are so disposed that a line between them passes through the center of gravity of the motor compressor unit and is perpendicular to the centerline of the drive shaft, said noise damping mounting including a third resilient connection between the motor compressor unit and the rigid supporting structure, which connection supports little or none of the weight of the motor compressor unit but limits the magnitude of oscillatory movement about said first two resilient connections, said third connection being so disposed that a plane between the first two connections and the third connection passes through the center of gravity of the motor compressor unit and is perpendicular to said drive shaft.

7. In a motor compressor unit mounting, the combination of a compressor, a motor for driving the compressor, a drive shaft extending between the motor and the compressor, a structure for retaining the motor and compressor as an operative unit, a rigid structure for supporting the motor compressor unit and a noise damping mounting for the motor compressor unit comprising two resilient connections extending between said unit and said rigid supporting structure, which connections support the major portion of the weight of the motor compressor unit and are so disposed that a line between them passes through the center of gravity of the motor compressor unit and is perpendicular to the centerline of the drive shaft, and said resilient connections being offset laterally from said compressor opposite the drive shaft so that vibrations produced by the unbalanced mass of the compressor apply rotational torque to the connections, said noise damping mounting including a third resilient connection between the motor compressor unit and the rigid supporting structure, which connection supports little or none of the weight of the motor compressor unit but limits the magnitude of oscillatory movement about said first two resilient connections.

8. In a motor compressor unit mounting, the combination of a compressor, a motor for driving the compressor, a drive shaft extending between the motor and compressor, a hermetically-sealed casing for enclosing and supporting the motor and compressor, a rigid structure for supporting the hermetically-sealed casing, and a noise damping mounting for the hermetically-sealed casing comprising two resilient connections extending between said hermetically-sealed casing and said rigid supporting structure, which connections support the major portion of the weight of the motor, compressor and hermetically-sealed casing and are so disposed that a line between them passes through the center of gravity of the motor, compressor and hermetically-sealed casing and is substantially perpendicular to a plane parallel to the centerline of the drive shaft.

9. In a motor compressor unit mounting, the combination of a compressor, a motor for driving the compressor, a horizontal drive shaft extending between the motor and compressor, a structure for retaining the motor and compressor as an operative unit, a rigid structure for supporting the motor compressor unit and a noise damping mounting for the motor compressor unit comprising two resilient connections ex-

tending between said unit and said rigid supporting structure, which connections support the major portion of the weight of the motor compressor unit and are so disposed that a line between them passes through the center of gravity of the motor compressor unit and is perpendicular to a plane parallel to the centerline of the drive shaft.

10. In a motor compressor unit mounting for refrigeration apparatus, including a condenser and an evaporator and refrigerant conduit connections between the motor compressor unit, condenser and evaporator, the combination of a compressor, a motor for driving the compressor, a drive shaft extending between the motor and compressor, a structure for retaining the motor and compressor as an operative unit, a rigid structure for supporting the motor compressor unit and a noise damping mounting for the motor compressor unit comprising two resilient connections extending between said unit and said rigid supporting structure, which connections support the major portion of the weight of the motor compressor unit and are so disposed that a line between them passes through the center of gravity of the motor compressor unit and is perpendicular to the centerline of the drive shaft, said resilient connections being positioned an appreciable distance from said compressor and opposite the drive shaft, so that vibrations produced by the unbalanced mass of the compressor apply rotational torque to the connections and some of said refrigerant conduits being coiled around the resilient connections.

11. In a motor compressor unit mounting for refrigeration apparatus, including a condenser and an evaporator and refrigerant conduit connections between the motor compressor unit, condenser and evaporator, the combination of a compressor, a motor for driving the compressor, a drive shaft extending between the motor and compressor, a structure for retaining the motor and compressor as an operative unit, a rigid structure for supporting the motor compressor unit comprising a plate type condenser including a sheet of metal having refrigerant passages provided thereon and a noise damping mounting for the motor compressor unit comprising two resilient connections extending between said unit and said plate condenser, which connections support the major portion of the weight of the motor compressor unit and are so disposed that a line between them passes through the center of gravity of the motor compressor unit and is perpendicular to the centerline of the drive shaft, said resilient connections being positioned an appreciable distance from said compressor opposite the drive shaft, so that vibrations produced by the unbalanced mass of the compressor apply rotational torque to the connections.

12. In a motor-compressor mounting, the combination of a compressor having a cylinder and a piston oscillated therein, driving means for said compressor, connecting structure between said compressor and driving means to combine the same into an operative unit, a supporting structure for said unit, and a vibration damping connection between said connecting structure and said supporting structure, said vibration damping connection comprising two resilient supports located on opposite sides of the center of gravity of said unit, said two resilient supports being so disposed that a straight line drawn between them is a substantial distance from a

straight line coinciding with the axis of said cylinder and is in a plane substantially at right angles to the axis of said cylinder, so that the vibrational movement of said unit produced by the oscillating piston produces a torsional stress on said resilient supports.

13. In a motor-compressor mounting, the combination of a compressor having a vertical cylinder and a piston oscillating therein, driving means for said compressor, a rigid structure connecting said compressor and said driving means into an operative unit, a rigid supporting structure for said unit, and a resilient vibration damping connection between said unit and said sup-

porting structure comprising two spaced-apart resilient supports stressed in shear by the gravitational forces on said unit, the two supports being so located that a straight line connecting them is horizontal, passes through the center of mass of said unit, and is spaced at all points a substantial distance from a line coinciding with the axis of said cylinder, so that the vibrational movement of said unit induced by said oscillating piston produces a torsional movement in said resilient supports.
